ABSTRACT OF THE DISCLOSURE

Sheet-handling apparatus including a multideck dryer, a feeder for feeding during a feed cycle successive charges of veneer sheets onto the infeed ends of different decks in the dryer, and an unloader including an intermittently-operated, motor-driven discharging mechanism for each dryer deck, operable to transfer sheets away from the offbearing end of the deck. Cam mechanism is provided which is positively driven by the feeder for rotation through a given angular distance during each feed cycle. The cam mechanism, during rotation, engages and actuates successive switches which, in turn, effect operation of different discharging mechanisms in the unloader. The cam mechanism is adjustable to vary the length of time that it engages a switch, thus to vary the duration of the operating periods of the discharging mechanisms.

This invention relates to sheet-handling apparatus, and, more particularly, to such apparatus which includes means for unloading charges of sheets from the offbearing ends of the different decks in a multiple-deck conveyor. A preferred embodiment of the invention is described herein in connection with a multiple-deck dryer for drying sheets of wood veneer.

A conventional veneer dryer includes multiple stacked conveyor decks which are power-driven (normally from a common drive means) to transport sheets through a chamber in the dryer where the sheets are heated and dried. Typically, green (or wet) sheets of veneer are fed, recurrently, in successive charges onto the infeed ends of different decks in a dryer by means of a feeder, such as the one described in U.S. Reissue Patent 24,843, issued July 12, 1960, entitled "Sheet Loading Mechanism for Multideck Conveyor." More specifically, such a feeder includes a loading conveyor mechanism which, during a feed cycle of the feeder, operates to transfer a charge of sheets onto each deck in the dryer. Proper positioning of the loading conveyor mechanism prior to transfer of a charge to a deck results from the action thereon of a rotating cam in the feeder that revolves once during each feed cycle.

Dried sheets may be transferred away from the offbearing ends of the dryer's decks by means of an unloader adapted to receive successive charges of sheets emerging from the dryer. The unloader includes a receiving station for each deck positioned adjacent the offbearing end thereof to receive and collect charges of sheets coming from the deck. Intermittently-operated discharging mechanism in the unloader may be operated to discharge sheets from the station, thereby clearing the station so that it may receive another charge. Sheets discharged from the unloader may then be carried away on an offbearing conveyor, or through other means, for grading and sorting, or for further processing.

For an unloader to operate without constant supervision some means must be provided for controlling the operating periods of the various discharging mechanisms in the unloader, whereby automatically, and after receiving a charge of sheets, the respective receiving stations in the unloader are cleared promptly to prepare them for

2

receiving other charges. Bottoming this invention is the concept of controlling the unloader operation through means positively coupled to movement of the feeder for the dryer, organized so that for each charge fed the dryer, another charge is unloaded in the unloader. The invention also features novel means for adjusting the timed relation of the operation of the unloader mechanisms with respect to movements in the feeder, so that the amount of time selected between the feeding of a charge and the unloading of a charge may be changed to take care of variable conditions such as the handling of different sheet lengths, etc. A specific feature of the invention is the provision of novel means enabling ready adjustment of the length of time that a given discharging mechanism will operate, and the making of such an adjustment while avoiding such a contingency as two discharging mechanisms operating simultaneously, which could cause considerable disarray of sheets on any means that collects the sheets discharged from the unloader.

Thus, a general object of the present invention is to provide, in a sheet-handling organization of the type outlined, novel means for controlling the operation of a sheet unloader which itself is controlled by movement of the feeder.

More particularly, an object of the invention is to provide, in sheet-handling apparatus comprising a multi-deck conveyor, a feeder for feeding successive charges of sheets sequentially to the infeed ends of different decks in the conveyor, and an unloader having a receiving station for each deck, novel means for controlling both the time at which unloading of a receiving station is performed and the duration of the unloading operation.

More specifically, an object is to provide, in apparatus of the type described wherein the feeder includes an element that revolves through a given angular distance during each feed cycle, novel rotating cam mechanism operatively connected to and positively driven by the element, such cam mechanism, by virtue of its connection to the element, also revolving through a given angular distance during each feed cycle. The cam mechanism, while revolving, effects operation of successive discharging mechanisms in the unloader.

According to the invention, a switch or control device is provided to reach discharging mechanism, operatively connected to a drive motor in the mechanism. The switch has a nonactuating state that it normally occupies, and an actuating state that it may be placed in to effect operation of its associated drive motor. The various switches are positioned adjacent the cam mechanism mentioned above, and with revolving of the cam mechanism, are engaged thereby and placed successively in their actuating states. The relative positions of the switches and cam mechanism may be adjusted to establish an appropriate timed relationship between the initiation of a feeding operation and that of a discharging or unloading operation.

An important part of the invention is the provision of novel cam mechanism of the type described which is readily adjusted to vary the length of time that it engages a particular switch to place it in its actuating state, thus to vary the operating period of the associated discharging mechanism.

These and other objects and advantages attained by the invention will become more fully apparent as the description which follows is read in conjunction with the accompanying drawings, wherein:

FIG. 1 is a simplified side elevation illustrating various units of sheet-handling apparatus including a multideck veneer dryer, a feeder for feeding sheets of veneer into the infeed end of the dryer, and an unloader constructed and operated according to the present invention for transferring sheets away from the offbearing end of the dryer;

FIG. 2 (second sheet of the drawings) is a view on a

larger scale than FIG. 1, illustrating novel cam mechanism constructed according to the invention driven by the feeder in FIG. 1;

FIG. 3 is a cross-section view, taken generally along the line 3—3 in FIG. 2;

FIG. 4 (third sheet of the drawings) is a side elevational view, also on a larger scale than FIG. 1, illustrating details of construction of the unloader in FIG. 1;

FIG. 5 (first sheet of the drawings) is a fragmentary cross-sectional view taken generally along the line 5—5 in FIG. 4; and

FIG. 6 (second sheet of the drawings) is a schematic diagram illustrating an electrical circuit connecting switches actuated by the cam mechanism of FIGS. 2 and 3 and discharging mechanisms employed in the unloader.

Turning now to the drawings, and referring first to FIG. 1, indicated generally at 10 is a conventional veneer dryer having an infeed end 10a and a discharge or off-bearing end 10b. The dryer shown includes a multiple-deck conveyor having five decks stacked one above the other indicated generally at 12, 14, 16, 18, 20. Each deck takes the form of a series of paired rolls (for simplicity, many of the rolls are not shown in FIG. 1) such as rolls 22 for deck 14. The rolls extend transversely of the dryer, and the pairs of rolls follow one another along the length of the dryer. The rolls in the various decks are suitably drivingly connected for simultaneous rotation to a common sprocket 24, and with turning of this sprocket, rotate to move veneer sheets through the dryer. The rolls in all of the decks turn at substantially the same speed. Sprocket 24 is driven by an electric motor 26 which is connected to the sprocket by a chain 28.

Aprons 12a, 14a, 16a, 18a and 20a indicated for reasons of simplicity as dashed lines in FIG. 1 comprise roll conveyors leading to the various decks in the dryer.

Positioned adjacent the infeed end of dryer 10 is a feeder 30 which operates in a feed cycle to feed successive changes of veneer sheets onto the infeed ends of different decks in the dryer. The feeder includes a frame 32, and a loading conveyor mechanism shown in dash-dot outline at 34 pivoted on the frame at 36 for swinging about a horizontal axis extending transversely of frame 32. In general terms, the loading conveyor mechanism feeds veneer sheets along a plane indicated in dash-dot outline at 38 which, with swinging of the mechanism, is moved into registry with the infeed ends of the aprons for the decks in the dryer. In FIG. 1, mechanism 34 has been swung to register plane 38 with the infeed end of apron 14a for deck 14.

During each feed cycle of feeder 30, the loading conveyor mechanism is swung into appropriate alignment with each of the different decks in the dryer by means such as a large cam mechanism (not shown) secured to a shaft 40 suitably journaled on frame 32. The cam engages the underside of the loading conveyor, and is constructed so that on being rotated by rotation of shaft 40, the loading conveyor swings on pivot 36 with its forward end swinging past the infeed ends of the aprons while dwelling for a short time on moving into registry with a particular apron. In the unloader shown a single revolution of shaft 40 in the direction indicated by the arrow, defines a feed cycle for the feeder, and in such a cycle, unloading conveyor mechanism 34 progresses from deck 20 upwardly to deck 12, and then back to deck 20.

Also secured to shaft 40 is a disc 42 having five finger elements, such as elements 44, projecting axially to one side of the disc, with the number of elements corresponding to the number of decks in dryer 10. The finger elements are positioned to actuate a switch 46 as the elements rotate with the disc and shaft 40. Switch 46, upon being actuated by a finger elements, causes means such as pinch rolls (not shown) provided in mechanism 34 to come together and feed a charge of sheets to a deck in the dryer.

Shaft 40 is rotated under power by means of a pair of

chains 48, 50 which connect the shaft to the output of a conventional variable speed gear box 52. The input of gear box 52 is connected through a chain 54 to previously-mentioned motor 26.

5 A detailed description of the construction and operation of feeder mechanism similar to that so far described herein may be found in previously-mentioned U.S. Reissue Patent 24,843.

10 Mounted on feeder 30 according to the present invention is a rotating cam mechanism or means 56. Mechanism 56 functions to coordinate the operate of a sheet unloader 58 (positioned adjacent the offbearing ends of the decks in the dryer) with that of feeder 30.

15 Considering the construction of and mounting provided for mechanism 56, and referring to FIGS. 1, 2, and 3, indicated at 60 is an elongated shaft paralleling shaft 40. The shaft is suitably journaled as by the bearing 62 shown in FIG. 2 which is mounted on frame 32. The left end of shaft 60 in FIG. 2 is threaded.

20 Secured to the right end of the shaft in FIG. 2, immediately to the right of bearing 62, is a sprocket 66. Sprocket 66 is connected to shaft 40 by means of a chain 68, and this driving connection is a positive one producing exactly one revolution of shaft 60 for one revolution of shaft 40.

25 Anchored to shaft 60 immediately to the left of bearing 62 in FIG. 2 is a spacer 70, and next to this spacer is an annular friction pad or agency 72. Pad 72 is made of a suitable high-friction material such as asbestos.

30 Cam mechanism 56, which is positioned to the left of pad 72 in FIG. 2, comprises a pair of cam elements 74, 76 mounted with shaft 60 extending loosely through their centers. The cam elements have substantially the same side profiles, and include radially projecting nodes 74a, 76a and arcuate slots 74b, 76b. The cam elements are locked together for movement as a unit by means of a nut and bolt assembly, or releasable locking means, 78 received in slots 74b, 76b. As can be seen in FIG. 3 where the cam elements are shown from the side, nodes 74a, 76a overlap one another. By releasing assembly 78, it will be apparent that the elements may readily be rotated relative to each other, to change the degree of overlap of the nodes. Slots 74b, 76b function as limit means limiting the amount of relative angular adjustment permitted between the elements. Thus, for all adjusted positions of the elements, and with assembly 78 locking the elements together, the nodes always overlap one another.

35 Cam element 74 is suitably secured to the right end of a sleeve 80 in FIG. 2, which is freely received on shaft 60. The left end of the sleeve carries a knurled knob 82. Screwed onto the threaded left end of shaft 60 in FIG. 2 is an internally threaded nut 84 with knob 86 attached. Knob 86 and pad 72 constitute a releasable clamping mechanism herein for, on turning of knob 86 to advance nut 84 inwardly on shaft 60, sleeve 80 is clamped against pad 72 to secure the cam elements in a given position on shaft 60. With loosening of nut 84, the cam elements may be shifted angularly on shaft 60 to a new position by turning of knob 82.

40 Also mounted on feeder 30 are five switch assemblies 88, 90, 82, 94, 96 with the number of such switch assemblies corresponding to the number of decks in dryer 10. The switch assemblies are distributed circumferentially about the cam mechanism. The assemblies are substantially the same in construction, and considering assembly 88 (which is illustrated in some detail in FIGS. 2 and 3), it includes a swingable arm 88a ganged to an electrical switch or control device shown in dashed outline at 88b (FIG. 3). Arm 88a carries a roller 89 on its outer end.

45 The arm is biased by a concealed spring in the assembly to the position shown in dash-dot outline in FIG. 3. On rotation of cam mechanism 56, roller 89 is engaged by nodes 74a, 76a to swing the arm to one side, as illustrated by the solid outline position of the arm in FIG. 3. With the arm in its first-mentioned position, switch 88b is in an

open or nonactuating state. With the arm swung to one side, and roller 89 along the radially outermost surfaces of nodes 74a, 76a, switch 88b is in a closed or actuating state. It will be apparent that the length of time that switch 88b remains closed depends upon the length of time that roller 89 rides on the outer surfaces of the nodes, and this time, in turn, depends upon the degree of overlap of the nodes. With cam mechanism 56 rotating, the nodes therein swing the arms in the various switching assemblies in the following order: 96, 94, 92, 90, 88, and then back to 96.

According to the invention, switch assemblies 88, 90, 92, 94, 96 function, with their respective switches closed successively by the cam mechanism, to energize different discharging mechanisms provided in unloader 58 for discharging onto an offbearing conveyor 97 sheets that arrive from the various decks in the dryer. In FIG. 1, such mechanisms for discharging sheets coming from decks 12, 14, 16, 18, 20 are represented by the blocks at 98, 100, 12, 104, 106, respectively.

Because the various decks in dryer 10 operate at the same speed, sheets fed sequentially to the different dryer decks during each feed cycle of feeder 30 emerge from the offbearing ends of the decks at a later time in the same sequence. Thus, for proper coordinated operation of the unloader, and with the unloader receiving sheets in the sequence just mentioned, it is important that the respective discharging mechanisms associated with the different dryer decks also operate in the same sequence.

Discharging mechanisms 98, 100, 102, 104, 106 are connected electrically to the switches in switch assemblies 88, 90, 92, 94, 96, respectively, by means of conductors 110, 112, 114, 116, 118, junction box 120, 122, cable 124, and conductors 110a, 114a, 116a and 118a.

Describing now the construction of unloader 58, and referring particularly to FIGS. 4 and 5, the unloader includes a frame 126 disposed in front of the offbearing end of the dryer, and a receiving station (shown in FIG. 4 at 128, 130, 132, 134, 136) for each deck in the dryer. In general terms, each receiving station comprises a short conveyor section operable to transport veneer sheets along a path which is a longitudinal extension of the path of travel of sheets through the dryer defined by the dryer deck feeding the conveyor means. Sheets received on a conveyor section are brought to rest with their ends aligned, and at a time thereafter, as determined by previously-mentioned cam mechanism 56, a discharging mechanism in the unloader operates to shift the sheets forwardly onto offbearing conveyor 97.

Considering structural details of the unloader, frame 126 comprises a series of uprights 138. Fastened to these uprights, on either side of the frame, is a series of longitudinally extending supports 140, with a pair of such supports provided in each receiving station for the conveyor means in the station.

Considering station 136, journaled on frame 126 by means of bearings, such as bearing 142 fastened to supports 140, and adjacent the infeed end of the unloader, is a transversely-extending roller 144. Roller 144 is a smooth-surfaced, nonpowered roller which functions to guide the ends of sheets traveling into the unloader, and to support the sheets while the same are pushed forwardly by dryer deck 20. Sheets emerging from the dryer are deflected so that they come into contact with roller 144 by means of a guide element 146 mounted on the infeed end of frame 126.

Directly in front of roller 144 is a pair of smooth-surfaced unloading rollers 148, 150 journaled on frame 126 by means of bearings 152 anchored to supports 140. Secured to one set of ends of rolls 148, 150 are sprockets 154, 156 which are used, as will be described, for rotating the rollers under power.

Superimposed over roller 150 is a roller 158. This roller has ends journaled on arms 160 that are pivoted at 162 through brackets 164 on supports 140. Roller 158 is urged

by gravity against roller 150, and functions to press veneer sheets that travel thereunder down onto roller 150 beneath it. Roller 158 may be provided with a yieldable outer covering, such as the rubber covering indicated at 166 in FIG. 5, whereby relatively even pressure is exerted by the roller downwardly on sheets traveling thereunder.

Under normal operating conditions, rollers 148, 150 (and roller 158 which is driven by roller 150) are rotated at a considerably faster speed than the rollers in the dryer. Thus, when veneer sheets engage these rollers, they are withdrawn from the dryer with the sheets traveling at a considerably greater speed than their travel speed through the dryer. Such speeding up of the withdrawn sheets produces a spacing between successive charges of sheets coming from a deck, and gives time to permit proper end alignment of the sheets before they are discharged onto conveyor 97.

Toward the offbearing end of the unloader from the rollers just described are smooth-surfaced, nonpowered rollers 168, 170 journaled on the frame of the unloader in bearing 172, 174, respectively. The function of these rollers is primarily to guide ends of sheets as such are shifted forwardly by rollers 150, 158. Directly adjacent the offbearing end of the unloader is previously-mentioned discharging mechanism 106 for station 136. Mechanism 106 includes a braking roller 178 for supporting the bottom faces of sheets advanced thereover, journaled in bearings 180 secured to supports 140. As can be seen in FIG. 5, the cylindrical surface of roller 178 is surrounded by a high coefficient of friction covering, such as rubber covering 182.

According to the invention, roller 178 is driven intermittently, as determined by cam mechanism 56, by means of an electric drive motor 184 mounted on frame 126. Motor 184 is drivingly connected to roller 178 by means of a drive chain 186. Chain 186 is trained over a sprocket 188 secured to one end of roller 178, a motor-driven sprocket 190 (FIG. 5), and an idler sprocket 192. Motor 184 is operated upon energizing of a motor-starting solenoid, indicated in block form at 194 which, together with the motor, also comprises part of discharging mechanism 106.

When motor 184 is running, roller 178 is rotated to cause veneer sheets supported thereon to shift to the left in FIG. 4, with such sheets being directed onto offbearing conveyor 97. When the motor is not running, roller 178 is stationary, and the outer surface of covering 182 constitutes a braking surface that slows down, and then stops, sheets traveling thereover. The braking force exerted by covering 182 on sheets is such that all sheets in a charge come to rest with their forward edges substantially aligned.

Station 136 also includes a roller 196 journaled on the frame and disposed above idler roller 168. This roller functions to support the trailing ends of sheets prior to operation of roller 178 to transfer such sheets away from the unloader.

The conveyor means in receiving stations 128, 130, 132, and 134 are similar in construction to the conveyor means just described, and the discharging mechanism in these other conveyor means are substantially the same in construction as discharging mechanism 106. Thus, mechanisms 98, 100, 102, 104, have rollers 198, 200, 202, 204, respectively, corresponding to roller 178, drive motors 206, 208, 210, 212, respectively, corresponding to motor 184, and motor-starting solenoids 214, 216, 218, 220, corresponding to solenoid 194.

As mentioned earlier, the unloading rollers in the various conveyor means, corresponding to rollers 148, 150, are rotated under power. Ordinarily, these rollers are rotated constantly by means which will now be described. Referring to FIG. 4, mounted on frame 126 beneath receiving station 136 is an electric motor 222 connected to a drive sprocket 224. Trained over the drive sprocket and sprockets such as sprockets 154, 156 secured to rollers

148, 150, is a drive chain 226. Also training the drive chain are idler sprockets 228, 230, 232, 234. With motor 222 running, the various unloading rollers are driven simultaneously in the same direction to transport sheets from the right to the left in FIG. 4.

Completing now a description of the electrical connections provided between the switch assemblies mounted on feeder 30 and the discharging mechanisms in unloaded 58, FIG. 6 illustrates such connections. Indicated at 236, 238 are a pair of main power supply conductors connected to a suitable source of AC power. Conductor 236 is connected through a switch 240 to an elongated conductor 242 which is connected by appropriate jumpers to one set of contacts in switches 88b, 90b, 92b, 94b and 96b of the switch assemblies. Conductor 238 is connected through a switch 244 (ganged to switch 240) to an elongated conductor 246 which is connected to one set of ends of the coils in motor-starting relays 214, 216, 218, 220 and 194. The opposite set of ends of such coils are connected, respectively, through conductors 110, 112, 114, 116, 118 to the other set of contacts in switches 88b, 90b, 92b, 94b and 96b.

Connected in series between conductors 242, 246 is a switch 248, and the coil 250a of a relay 250. Relay 250 also includes normally open switches 250b through 250f which are connected in series, respectively, between conductors 110, 112, 114, 116, 118, and conductor 242.

Shown at 252, 254 is another pair of power supply conductors also connected to a suitable source of AC power. Conductors 252, 254 are connected through ganged-together switches 256, 258, respectively, to conductors 260, 262, respectively. Conductor 260 is connected to one set of input terminals in drive motors 206, 208, 210, 212, 184. The other input terminals in these motors are connected through the normally open switches 214a, 216a, 218a, 220a and 194a of their associated starting solenoids to conductor 262. Thus, each drive motor is connected in series between conductors 260, 262 through the switch in its associated motor-starting solenoid.

Explaining briefly the operation of the circuit in FIG. 6, to place the circuit in an operative condition, switches 240, 244, 256, 268 are closed. Normally, switch 248 is left open whereby coil 250a is non-energized, and switches 250b-250f are open. The length of time that each switch is held closed depends upon the length of time that the roller on the arm connected to the switch rides on the outer surfaces of the nodes in the cam mechanism.

When one of the switches, for example switch 96b closes, power is then supplied to energize the coil in its associated motor-starting solenoid 194, and switch 194a closes. Upon closing of switch 194a, power is supplied to operate drive motor 184 in discharging mechanism 106, whereupon sheets that are at rest upon roller 178 are shifted out of the unloader and onto conveyor 97. Motor 184 continues to operate so long as the coil in solenoid 194 is energized, and this depends upon the length of time that the roller on the arm in switching device 96 rides upon the outer surfaces of the nodes in the cam mechanism. A similar operation takes place in the other discharging mechanism with closing of the other switches distributed about mechanism 56.

When it is desired to clear simultaneously all sheets held in the unloader, independently of the action of cam mechanism 56, switch 248 is closed to energize relay coil 250a. With energizing of this coil, switches 250b-250f close to supply power to the coils in all of the motor-starting relays in the discharging mechanisms.

Describing now how the apparatus shown herein performs as a whole, and explaining how the operation of unloader 58 is coordinated according to the invention with the operation of feeder 30, initially, certain adjustments are made in cam mechanism 56. More specifically, with knob 86 loosened on shaft 60, and assembly 78 also loosened, cam elements 74, 76 are rotated relative to one another to produce proper offset and a given degree of

overlap in nodes 74a, 76a. Thus, with the length of sheets to be processed known, the nodes are offset sufficiently to produce drive motor operating periods which will insure complete discharge of each charge of sheets from the unloader. The offset selected is not so great as to cause two discharging mechanisms to operate at once. Assembly 78 is then tightened to fasten the two cam elements together for operation as a unit.

Next, through manipulation of knob 82 and sleeve 80, the cam mechanism is adjusted to have the proper angular position on shaft 60. More particularly, the cam mechanism is positioned on the shaft whereby, with motor 26 powering the dryer decks and turning shafts 40, 60, and with motor 222 driving the various unloading rollers in the unloader, the nodes in the cam mechanism close switches 88b, 90b, 92b, 94b, 96b successively at the proper time to produce appropriate clearing by the discharging mechanisms. After such an adjustment, knob 86 is turned to clamp mechanism 56, sleeve 80, and knob 82 between washer 72 and nut 84 to secure the cam mechanism for rotation with shaft 60.

With cam mechanism 56 properly adjusted, on each rotation of shaft 40 whereby one cycle of the feeder is performed, one complete cycle of unloading by the unloader results. For each charge in a cycle that is fed into the dryer, another charge is unloaded. The relationship is a positive one, by reason of the positive drive connection between shaft 40 and cam mechanism 56. Adjustable cam mechanism 56 permits adjustments readily to be made whereby the timing desired for a particular operation is obtained.

Such coordination obviously results in a highly efficient flow of sheets through the dryer and unloader. It will be appreciated that an important contributing feature and advantage herein is that the cam mechanism includes novel relatively rotatable cam elements having nodes that can be adjusted to different overlapping positions. With such adjustment possible, the lengths of the operating periods for the discharging mechanisms can easily be varied to accommodate sheets having different lengths. Thus, the mechanisms can always be operated for just the right amounts of time, and power is conserved. In addition, such a provision is useful in adjusting the configuration of the cam mechanism to avoid the possibility of more than one motor-actuating switch being closed at a time.

Further, with the angular position of the cam mechanism on shaft 60 being adjustable, and with means provided for clamping the mechanism in place when properly adjusted, it is a relatively simple matter to position the cam mechanism whereby the various discharging mechanisms operate at the proper times. Once the cam mechanism is clamped in place for rotation with the shaft, and with the switches that are associated with the discharging mechanisms properly distributed about and adjacent the cam mechanism, the discharging mechanisms are then operated completely automatically and in appropriate succession. Accordingly, and because feeding and discharging of sheets takes place at the same rate, and in directly corresponding sequences, the dryer is always properly filled with sheets, and there is no problem of sheets stacking up in the unloader.

While a preferred embodiment of the invention has been described herein, it is appreciated that variations and modifications may be made without departing from the spirit of the invention. For example, an unloader according to the invention may easily be provided which will accommodate more or less than five conveyor decks, with appropriate cam mechanism and switches also provided to coordinate the operation of the discharging mechanisms in such an unloader.

It is claimed and desired to secure by Letters Patent:

1. In sheet-handling apparatus including a multiple deck conveyor and a feeder with means operable in a feed cycle to feed successive charges of sheets onto the

infeed ends of different decks in said multiple deck conveyor, and an unloader comprising, for each deck, an intermittently-operated discharging mechanism for removing sheets from the off-bearing end of the deck,

a control device controlling each discharging mechanism having a first state that it occupies when the discharging mechanism is not operating, and a second state that it occupies when the discharging mechanism is operating,

said control devices for the various discharging mechanisms being positioned adjacent one another in a continuous path, and

rotating cam means operatively connected to and positively driven by said feeder for revolving through a predetermined angular distance during a feed cycle of the feeder,

said cam means on being rotated engaging successive devices in said path during each feed cycle to place such successive devices in their said second states,

said cam means comprising a pair of cam elements mounted adjacent each other and relatively adjustable by relative angular displacement about a common axis, said cam elements including nodes adjacent their circumferences which collectively form a continuous node surface which is adjustable in length by relative angular displacement of the cam elements, such adjustment changing the time that the cam means engages a given device on rotation of the cam means.

2. The apparatus of claim 1, wherein said cam means

further comprises releasable locking means releasably locking said cam elements in a given adjusted position.

3. The apparatus of claim 2, wherein said cam means further comprises means limiting the amount of relative angular adjustment permitted between the elements.

4. The apparatus of claim 1, wherein said cam means is operatively connected to said feeder by means comprising a shaft supporting said cam elements with the elements being rotatable on the shaft for adjustment purposes, and releasable clamping means operatively interposed between said shaft and elements releasably clamping the elements in place for turning with the shaft.

5. The apparatus of claim 4, wherein said releasable clamping means comprises a friction agent interposed between one cam element and said shaft, and means adjustable to force said cam element toward said friction agency.
